Primary Examiner — Brian N Vinson(74) *Attorney, Agent, or Firm* — Tsircou Law, P.C.(57) **CLAIM**

We claim the ornamental design for a light assembly, as shown and described.

DESCRIPTION

FIG. 1 a front, left perspective view of a light assembly of the new design.

FIG. 2 is a back left perspective of the light assembly of FIG. 1.

FIG. 3 is a bottom view of the light assembly of FIG. 1.

FIG. 4 is a left elevational view of the light assembly of FIG. 1.

FIG. 5 is a top view of the light assembly of FIG. 1.

FIG. 6 is right elevational view of the light assembly of FIG. 1; and,

FIG. 7 is back elevational view of the light assembly of FIG. 1.

The dashed lines depict environmental aspects and form no part of the claimed design.
